BLADE PACKAGE

Joseph Muros, Newtonville, Mass., assignor to
The Gillette Company, a corporation of Delaware

Application March 5, 1948, Serial No. 13,230

13 Claims. (Cl. 206—16)

1

This invention relates to razor blade dispensing packages of the type in which a small number of unwrapped blades are enclosed in an inexpensive wrapper to form a booklet of blades with the blades being detachably secured by frictional engagement of two opposite sides of the wrapper. The invention is herein exemplified as embodied in a package of safety razor blades of the double-edged type, although it is not limited to that type or to blades of any specific shape.

An object of the invention is to improve blade dispensing devices and to provide a simplified container which is conveniently made by folding a single strip of flexible material upon itself to form a blade sheath in which a limited number of double-edged blades may be received to constitute a compact booklet of blades. Another object of the invention is to devise an outstandingly cheap means of retaining the several blades in a relatively secure position from which they may be readily detached or removed as desired without difficulty or danger of cutting the user.

In packaging a very small number of blades, emphasis is sharply on low cost of materials and assembly, and arrangements for securing each blade individually are therefore less desirable. The razor blade dispensing booklet of the invention furnishes one satisfactory solution by combining with a folded wrapper, a single fastening member which may be engaged externally of the folded portion, thus involving only a very simple fastening operation.

An important feature of the invention therefore is a razor blade dispensing package made up of a flexible carrier strip which is folded upon itself to form a razor blade sheath. Adjacent folded portions constituting the sheath are resiliently held against one another by a clinching member which may be of the simple gripper type acting solely from outside the wrapper, or which may pass through the wrapper. The clinching member, either in the form of a simple resilient gripper element or in a form in which it pierces the wrapper, serves to exert forces against two opposite surfaces of the folded strip and holds the blades and immediately adjacent sheath portions in compressed relation against one another in a relatively firmly secured position. When the cover portion of the sheath is turned back, the blades may be selectively withdrawn by pulling them from between the compressed sides of the sheath which contract as the supply of blades diminishes.

Another important feature of the invention is the provision of a specific type of clinching mem-

ber arranged to bear at two spaced-apart points on one side of the sheath member and at a point on the other side of the sheath member lying between the said first two points, in a manner such that a bowing or bending action is caused to take place transversely of the blades and adjacent sheath portions. One effect of the bowing is to increase the frictional engagement of the blades against one another, thus imparting an added measure of stability and holding power to the razor blade pack as a whole.

Another feature is a clinching member modified to include guide rib means which are preferably arranged to project through slots in each of the blades to aid in securing the blades and holding them in substantial alinement within the sheath. The guide rib means may conveniently be formed as an integral part of the clinching member with suitable slots being provided in the sheath member in register with the rib so that the latter may pass freely therethrough. Openings may also be provided in the back of the wrapper and a separate wall portion added thereto for the purpose of furnishing a used blade receptacle at the back side of the wrapper.

These and other objects and novel features of the invention will be best understood and appreciated from the following description of the preferred embodiment selected for purposes of illustration and shown in the accompanying drawings, in which

Fig. 1 is a perspective view illustrating a blade wrapper of the invention in which blades are held by a clinching member bearing at the external surfaces only of the wrapper;

Fig. 2 is a cross section taken on the line 2—2 of Fig. 1, further illustrating the transversely warped formation of the blades resulting from pressure of the clinching member;

Fig. 3 is another cross section taken on the line 3—3 of Fig. 1;

Fig. 4 is a perspective view of a blade wrapper containing a small number of stacked blades and further illustrating a clinching member of the staple type which pierces the wrapper as well as bearing on opposite sides;

Fig. 5 is a perspective view illustrating a wrapper modified to include a used blade compartment with a part of the wrapper having been broken away to disclose a used blade in the compartment;

Fig. 6 is a cross section taken on the line 6—6 of Fig. 5;

Fig. 7 is a perspective view of a blade wrapper including a clinching member of the type hav-

ing a guide rib means which passes transversely through the wrapper and also the blades;

Fig. 8 is a perspective view illustrating the blade package of Fig. 7 as viewed from its under side;

Fig. 9 is a cross section taken on the line 9—9 of Fig. 7;

Fig. 10 is a perspective view of a blade dispensing package having a clinching member with a modified guide rib means;

Fig. 11 is a perspective view of a blade package similar to that illustrated in Fig. 10 with the under side of the package having been partly broken away to disclose a used blade compartment formed therein;

Fig. 12 is a cross section taken on the line 12—12 of Fig. 10;

Fig. 13 is a composite view showing each of the several elements utilized in constructing the blade package illustrated in Figs. 10—12 inclusive;

Fig. 14 is a perspective view of a blade wrapper having a clinching member constructed with another modification of guide rib means;

Fig. 15 is a cross section taken on the line 15—15 of Fig. 14;

Fig. 16 is a perspective view showing the under side of the blade package indicated in Figs. 14 and 15;

Fig. 17 is a composite view further showing the elements utilized in forming the package shown in Figs. 14—16 inclusive;

Fig. 18 is a perspective view illustrating a blade wrapper provided with a clinching member and guide rib means formed integrally with the wrapper;

Fig. 19 is a composite view showing the clinching member and the wrapper element utilized in forming the package of Fig. 18; and

Fig. 20 is a cross section taken on the line 20—20 of Fig. 18.

The blade dispensing package of the invention, including the several forms of clinching means shown, is designed especially for use with a relatively small number of blades and although not limited to any specific number, is especially suitable for containing and dispensing a pack of four or five blades. The various structural details, together with the features and advantages hereinafter set forth, should be read with reference to a four or five blade pack, bearing in mind the low cost requirements connected with such relatively small units.

The principal parts of the blade dispensing package of the invention include a blade carrier strip or wrapper which is folded upon itself to form an inclosure and a clinching member for gripping the folded end of the wrapper to constitute a razor blade sheath in which a small number of blades may be slidably received. The fold-line along which the material is bent, although not necessarily fixed at any given point, is in general chosen in such a way as to result in forming an inclosure and sheath portion of a depth less than the length of the blades to allow exposed ends of the blades to project outwardly in a convenient position for removal by the user. It is inherent in the design of the package that a clinching member of some resiliency be employed and the use of the term "clinching" means or "member" in the specification is understood to refer to a resilient type of fastening or gripping means which in all cases is adapted to engage externally the two opposite sides of a blade wrapper, thus to securely and constantly maintain light compres-

sive forces which firmly hold the blades and adjacent wrapper portions against one another.

For example, in one simple form of the invention as shown in Figs. 1—3 inclusive, in which the clinching member operates from the external surfaces only of the wrapper, numeral 20 refers to a flexible wrapper which may be of any suitable material such as paper, plastic, or similar substance occurring in sheet form. One end 22 of the strip is folded over upon itself as indicated in Fig. 1, to provide a blade sheath in which are slidably received a plurality of razor blades 24, arranged in longitudinally and progressively overlapping relation. The folded end 22 is compressed against the blades as shown, by means of a clinching member 26 of the type commonly referred to as a paper clip, having wire ends or legs which are spread apart and slidably engaged over the opposite sides of the folded wrapper extremity 22. In the particular form of clip noted, there are two spaced ends of the clip bearing against one side of the wrapper and another end bearing against the opposite side of the wrapper at a point between the said first two clip ends. As the clips seek to assume their normal position, they exert compressive forces on two sides of the blade package for compressing the blades and immediately adjacent strip portions against one another, thus producing an appreciable frictional engagement, by means of which the blades are held in fixed relation in the sheath. The length of the sheath is chosen so as to leave exposed ends of the blades projecting outwardly in a convenient position for withdrawal.

It will be observed that application of a compressive force occurs against one side of the wrapper at a point substantially midway thereof, while two other compressive forces are exerted on the other side of the wrapper at points more nearly adjacent the outer edges and as a result of this arrangement there is induced a flexing of the blades and adjacent carrier strip portions in such a manner that they are bent or bowed transversely of themselves. Advantage is taken of the fact that the median slots of the blades facilitate bending along a longitudinal axis. The bowed effect is more clearly disclosed in Fig. 2. The principal advantage derived from the bowed shape of the blades is increased frictional engagement of each blade with respect to an adjacent blade and increased stiffness of the individual blades, thus imparting greater stability and rigidity to the pack as well as decreasing the possibility of accidental displacement of a blade. Such a combination of a limited number of blades and single carrier strip folded upon itself comprises a simple, cheap and easily assembled unit, convenient to handle and well adapted to forming a sales package for dispensing a limited number of razor blades. If desired, an outer covering may be applied to seal the blades against moisture.

The blade package illustrated in Figs. 5 and 6 is similar generally to the package above described including however a used blade compartment formed by attaching at the under side of the wrapper 20 an exterior wall 30, which may be secured, for example, by adhesive applied along its edges. It may also be desired to form the wall 30 integrally with the wrapper so that there is provided at least one connecting edge by which the wall portion may be folded over on adjacent portions of the wrapper. As may be seen in Fig. 5, the partition element 30 is formed

with a slot 32 having a width slightly exceeding the width of one of the blades 24, and the blade 24 may, when desired, be inserted in this slot and advanced forwardly until completely received in the space between the wall 30 and the adjacent side of the wrapper.

In the form of blade retaining means illustrated in Fig. 4, compressive forces are again applied from two opposite external surfaces of a folded wrapper 34 by means of a clinched member 36. However the clinched member in this instance is designed to pierce the folded end 38 in the manner customary with a fastening of the staple type in which ends of the staple pass through the wrapper and are bent over to resiliently grip the intervening wrapper portions. Blades 40 are received and held in the sheath portion by the compressive forces exerted. Fig. 4 also illustrates a stacked arrangement of the blades, one directly above another, which may be resorted to in place of the longitudinally overlapping arrangement disclosed in Figs. 1-3 inclusive.

In Figs. 7-9 inclusive, there has been illustrated the combination of a blade wrapper with a clinched member which not only applies compressive forces at two outer sides of the wrapper, but also passes through both the wrapper and the blades to constitute a novel guide rib means. Blades 44 arranged in longitudinally overlapping relation, are slidably received in the manner already described, in a sheath formed by folding a wrapper 46 upon itself to present a folded end 48 of a length less than the length of any one of the blades 44. A clinched member 50 of resilient character is slidably engaged against the folded portions of the wrapper in the same general way common to the clinched members already noted. Along that portion of the clinched member 50 which occurs adjacent to the under side of the wrapper 46 are formed guide rib portions 52 and 54, which may conveniently be constructed by cutting out portions of the clinched member and bending them over into a right angularly extending position so that they lie in spaced-apart relation and in parallel alinement. The under side of the wrapper is cut away to leave slots through which the guide ribs 52 and 54 are allowed to pass. The upper side of the clinched member 50 may also be cut away to define a slot 56 which is in register with the guide ribs 52 and 54, and the portion of the wrapper occurring between the top of the clinched member 50 and the uppermost blade 44 is also recessed to define a slot through which the guide ribs may extend. The guide rib arrangement described functions to maintain all of the blades in parallel alinement with one another, and moreover the rib tends to check displacement of the blade in a longitudinal direction to a limited degree. It will be observed that in removing a blade from the blade pack it must be passed over the rib without too great interference and this operation is provided for by forming the top edges of the rib portions with a bevel which gradually meets the plane in which the lowermost blade is located. If desired, the inner lowermost end of the beveled edge may be slightly rounded. When a blade is pulled away from the sheath, its central portion immediately adjacent to the end of the slot is caused to slide upwardly and over the rounded end and then along the beveled edge so that a releasing effect is achieved. In using a clinched member with

the integral rib structure described, it may also be desirable to secure the under side of the clinched member with tabs 60. It may also be found desirable to provide the body portion of the wrapper with an intermediate fold line 62 which is located to allow the wrapper to be bent or flexed away from the group of blades, thus leaving them in a somewhat more accessible position for handling. The cover 64 is formed with an opening 66 to register with the rib when in a closed position.

An alternate method of constructing a guide is to form a clinched member with an external or separately applied projection in the manner suggested in Figs. 10-13 inclusive. As noted therein, a wrapper 70 is folded upon itself to present an overlapping end 72 which forms a blade sheath portion. The end 72 is secured as before by a clinched member 74 which frictionally secures the blades 76. Ribs 78 formed in the member 74 (Fig. 13) extend upwardly, projecting through the opening 80 in the upper wall of the clinched member 74. The rib passes through a slot 82 in the wrapper 76 as may be more clearly seen in Fig. 13. Combined with the back of the wrapper is a wall or panel 84 which may be separately secured to the wrapper in any desired manner as by adhesive, and which overlies the under side of the clinched member. As a result of this arrangement, it will be seen that the clinched member serves the additional function of providing a smooth, hard bearing surface along which the end of a blade may be passed as the blade is inserted in the compartment formed by itself and the partition 84. Since the clinched member is preferably formed of a material such as metal or other relatively hard substance, a durable surface is presented along which a number of blades may be easily slid without danger of cutting.

The rib construction may be utilized at other points than at the under side of the clinched member as has been indicated in Figs. 14 and 15 in which a wrapper 90 with folded end 92 is secured by a clinched member 94, whose upper side as viewed in Fig. 15 is formed with a corrugation 96 constituting a locating rib of the same general character described. The folded end 92 is in this case provided with a slot 98 through which the rib may extend into engagement with a razor blade slot. The rib 96 and wrapper may be more clearly seen in Figs. 16 and 17.

It may further be desired to utilize a locking rib in various other ways as for example by forming a rib portion directly in the wrapper instead of in the clinched member, and such an arrangement has been suggested in Figs. 18, 19 and 20, in which a wrapper element 100 is formed with folded end 102, containing blades 104 which are clinched in place by a member 106. The wrapper is constructed with a rib or corrugated portion 108 projecting upwardly in position to register with the slots of blades 104. Fig. 20 shows the rib engaged with the blades 110 in the manner described.

Having thus disclosed my invention and described in detail illustrative embodiments thereof, I claim as new and desire to secure by Letters Patent:

1. A razor blade dispensing package comprising a plurality of bare blades disposed one against another in progressively overlapping relation, a wrapper element folded upon itself and about one end of the blades to form a blade sheath, one of the folded portions having a

length less than the length of any one of the blades, clinching means embracing the folded portion of the sheath and including resiliently connected sections, each of the sections bearing at a respective outer surface of the sheath for compressively holding the blades and immediately adjacent sheath portions against one another, and a folded cover portion formed as a part of the wrapper element and covering the ends of the blades projecting beyond the sheath.

2. A razor blade dispensing package as set forth in claim 1 further characterized in that said clinching means is shaped to bear along only the center region on one side and two opposite side edges only of the blade sheath on the other side for causing the blades and immediately adjacent sheath portions to assume a transversely bowed position.

3. A razor blade dispensing package as set forth in claim 1 further characterized in that said clinching means comprises a clip having two spaced-apart extremities for engaging one side of the sheath and a third extremity positioned intermediate the said first two extremities for engaging the opposite side of the sheath for bending the blades about their longitudinal axis.

4. A razor blade dispensing package as set forth in claim 1 further characterized in that the blades are slotted and stacked so that the slots of the individual blades are substantially in alignment with each other, and the clinching means includes a guide rib projecting through the wrapper and blade slots and maintaining the blades in alignment with one another.

5. A razor blade dispensing package as set forth in claim 4 further characterized in that said guide rib is integral with said clinching means on one side thereof and extends into a registering slot in the other side of said means.

6. A razor blade dispensing package as set forth in claim 1 further characterized in that the blades are slotted and stacked so that the slots of the individual blades are substantially in alignment with each other, and a guide rib projects through the blade slots for maintaining the blades in alignment with one another in the stack, the guide rib having an inclined upper edge portion for facilitating the withdrawal of the blades.

7. A razor blade dispensing package as set forth in claim 1 further characterized in that the blades are slotted and stacked so that the slots of the individual blades are substantially in alignment with each other, and the clinching means includes a guide rib formed on one side thereof and extending through the sheath and slots in said blades to maintain the blades substantially in alignment, said guide rib including a channel-shaped portion whose sides are struck from said clinching means and bent over into parallel spaced-apart relation, the upper edges of said guide rib being bevelled to facilitate blade withdrawal.

8. A razor blade dispensing package as set forth in claim 1 further characterized in that said blades are slotted and stacked so that the slots of the individual blades are substantially in alignment with each other, and one side of said clinching means is depressed to form a centrally disposed rib, the portion of the sheath lying im-

mediately below said rib being recessed to receive said rib, said rib passing through the blade slots and resting against the other side of the sheath.

9. A razor blade dispensing package as set forth in claim 1 further characterized in that the blades are slotted and stacked so that the slots of the individual blades are substantially in alignment with each other, and means project through the blade slots for the purpose of maintaining the blades in substantial alignment in the sheath.

10. A razor blade dispensing package as set forth in claim 1 further including a slotted wall secured along its edges at one side of the sheath and enclosing one section of said clinching means, and forming with the sheath a used blade compartment.

11. A razor blade dispensing package as set forth in claim 1 further including a wall secured along three edges to the sheath to form therewith a used blade compartment.

12. A razor blade dispensing package as set forth in claim 1 further including an exterior wall located below the clinching means and enclosing one of the sections thereof, said exterior wall being edge-secured to the sheath and forming between itself and said enclosed section a used blade compartment, said enclosed section serving to guide the leading end of incoming used blades as the latter is advanced into said compartment.

13. A razor blade package comprising a plurality of stacked bare blades disposed one against another, a wrapper element folded upon itself and about one end of the blades to form a blade sheath, the bottom portion of said sheath being of a length at least as long as the stack of blades and a top portion of said sheath having a length less than the length of the stack of blades, clinching means embracing the folded portion of the sheath including resiliently-connected sections offset laterally with respect to each other, each of the sections bearing on a respective outer surface of the sheath for compressively holding the blades and immediately adjacent sheath portions against one another in transversely bowed condition and the sections contracting as the supply of blades diminishes, the sheath also including another top portion covering the ends of the blades projecting beyond the first-mentioned top portion of said sheath and being of a length sufficient to extend under the latter to form a closed package.
